RELEASING CLAMP

Kent A. Hawley, Baltimore, Md., assignor to
Locke Insulator Corporation, Baltimore, Md., a
corporation of Maryland

Application March 12, 1931. Serial No. 522,080

11 Claims. (Cl. 248—31)

The invention relates to clamps for supporting the conductors of high tension transmission lines and has for its general object the provision of a novel clamp which will release its grip upon the 5 conductor under certain circumstances.

It is well known that it is customary to support a conductor by means of a clamp suspended from the lower end of a string of insulators. It frequently occurs that as the result of the accumulation of ice or sleet upon the conductor a strain is set up which swings the string of insulators to one side to an abnormal and dangerous extent. The same thing occurs in case the conductor breaks at either side of the clamp. It is with 10 these facts in view that I have devised the present invention which has for an important object the provision of a clamp which will remain effective even though the string of insulators should become tilted to a limited extent, as they may of course under the influence of wind, the construction being such that the clamp will not release its grip until the safe angularity of the insulator string has been exceeded.

A very important object of the invention is to 25 provide a clamp in which the movement of the parts to released position is away from the conductor instead of toward it, thereby insuring operativeness of the clamp even though it may be encrusted with ice or sleet.

Another object is to provide a clamp in which the release is effected by a tripping action, the parts being undisturbed until the suspension means swings beyond a predetermined limit.

A further object is to provide a clamp of such 35 construction that the force with which it grips the conductor may be varied.

A more specific object is to provide a clamp embodying lever means for applying the clamping pressure upon the conductor.

An additional object is to provide a device of 40 this character which will be simple and inexpensive to make, easy to assemble and install, positive in action, efficient and durable in service, and a general improvement in the art.

To the attainment of the foregoing and other 45 objects and advantages, the invention preferably consists in the details of construction and the arrangement and combination of parts to be hereinafter more fully described and claimed, and illustrated in the accompanying drawing in which:

Figure 1 is a side elevation of a clamp constructed in accordance with my invention, parts 55 being broken away and in section and the releas-

ing position being indicated by dot and dash lines.

Figure 2 is a plan view with the suspension means in section, and

Figure 3 is a vertical cross sectional view taken on the line 3—3 of Figure 2.

Referring more particularly to the drawing I have shown the clamp as comprising a lower clamping member 10 which may conform to the generally accepted standards or which might be of special construction. This lower member has a conductor receiving groove 11 therein which is arcuate in cross section and longitudinally curved so that the ends 12 will be of bell-like formation so as to avoid bringing any bending strains upon the conductor in the event of vibration or "dancing" of the conductor. Co-operating with this lower member 10 is an upper clamping member 13 similarly formed with a transverse groove or seat 14 for the reception 70 of the conductor 15. The lower member 10 is formed at its sides with apertured bosses 16 through which pass U-bolts 17 which of course straddle the upper clamping member 13 and the conductor and which are provided with nuts 18, 80 it being preferable to locate split spring washers or the like between the nuts and the undersides of the bosses so as to give a certain amount of resilience.

The means for connecting the clamp with a 85 string of insulators, not shown, preferably comprises links 20 apertured at 21 or otherwise formed for connection with whatever element is provided at the lower end of the insulators. These links pivotally support the clamp and are 90 represented as having elongated slots 22 in their lower ends engaged upon trunnions 23 which project laterally from the lower member 10 and which preferably have downwardly prolonged or overhanging heads 24 which overlie the links at 95 the lower ends of the slots therein and which therefore prevent the links from any disengagement.

I provide clamping means cooperating with the U-bolts 17 for forcing the clamping members into gripping relation to the conductor and this means includes levers 25 which have their toe portions 26 engaged beneath the bight portions of the U-bolts and which have heel portions 27 fulcruming on the upper member 13. 100 These levers curve, extend toward each other and have their inner ends located between the links 20. Cooperating with these levers are trip actuated retaining members 28 pivoted at 29 upon opposite sides of the upper clamping mem- 105

ber 13 and formed on their confronting faces with lugs 30 which extend inwardly and which normally overlie outwardly extending lugs 31 on the inner ends of the levers 25 so that these levers 5 will be held down in clamping relation to the clamping members. These members 28 have outstanding horns or projections 32 thereon embracing the links 20 but normally spaced therefrom so as not to be engaged by the edges of the links 10 unless the links are tilted beyond a certain angularity with respect to the clamp.

The normal position of the parts is as shown in Figure 1 and it will be observed that owing to the engagement of the lugs 31 beneath the 15 lugs 30 the levers 25 reacting against the upper clamping member 13 at the fulcrum points 27 will hold the clamping members firmly upon the conductor. The degree of pressure can be adjusted by means of the nuts 18. Normal swinging movement 20 of the insulator string and links 20 is permissible but if the angularity exceeds a certain degree, as it will in the event of breakage of the conductor or as the result of an accumulation of ice or sleet at one side of the clamp, the links 25 will engage against one set or other of the horns or projections 32 and rock the retaining members 28 upon their pivot 29 whereupon the lugs 30 will ride off from the lugs 31, thereby releasing the downward pressure upon the levers and permitting 30 them to swing upwardly at their inner ends. Owing to the peculiar shape of the levers and the location of their fulcrum points they will then cease to exert pressure upon the U-bolts and the clamping members become ineffective or release their grip upon the conductor so that it can slide through until the strain at opposite sides of the clamp will be equalized. When normal conditions are restored the clamp will not regrip the conductor automatically but will require 40 the services of a mechanic. This is of advantage as particularly in the case of an armored cable it would not be advisable to have the clamping action resumed in case the armor had slipped entirely through the clamp.

45 From the foregoing description and a study of the drawing it will be apparent that I have thus provided a very simple clamp composed of but few parts and which will efficiently perform the functions for which it is intended. Particular note should be given to the feature that the releasing of the grip involves a movement of the parts upwardly or away from the conductor. This is far preferable than if the reverse were true as it is clear that if release involved movement of the parts downwardly or toward the conductor the action might be very seriously interfered with in case of an accumulation of ice on the clamp itself as such ice would have to be crushed before the parts could move. Any 50 ice on the clamp will not noticeably hinder the releasing action. It is thought that the construction, operation and advantages should be readily apparent to one skilled in the art without further explanation.

60 While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the 65 scope of the claims hereunto appended.

Having thus described the invention, I claim: 70 1. A suspension clamp for a conductor comprising a pair of clamping members, suspension means therefor, lever means engaging one clamping member at a plurality of points for normally maintaining the clamping members in clamping engagement upon the conductor, and means directly pivoted on one clamping member for maintaining the levers in effective position cooperating with the suspension means for releasing the clamping action of the lever means upon movement of the suspension means beyond a predetermined extent. 80

2. A conductor suspension clamp comprising clamping members, means including a plurality of levers normally maintaining the clamping members in clamping relation, means directly pivoted on one clamping member for holding the levers in effective position, suspension means, and means cooperating with the suspension means for moving said holding means out of engagement with the levers upon movement of the suspension means beyond a predetermined extent. 90

3. A conductor suspension clamp comprising clamping members engageable upon a conductor, lever means reacting against one clamping member at a plurality of spaced points for normally maintaining a clamping action upon the conductor, swingable means pivoted on said one clamping member normally maintaining said lever means effective, suspension means, and means cooperating with the suspension means upon movement thereof beyond a predetermined extent for swinging said means and rendering said maintaining means ineffective. 100

4. A conductor suspension clamp comprising a pair of clamping members engageable upon a conductor, means reacting against one clamping member at opposite sides of the center thereof for normally maintaining the clamping members in clamping engagement upon the conductor, means pivoted on the clamping member which is engaged by the levers for normally maintaining said means effective, suspension means, and means operable upon abnormal movement of the suspension means for releasing said maintaining means. 110

5. A conductor suspension clamp comprising a pair of clamping members, U-bolts carried by one member and straddling the other, levers engaged within the bight portions of the U-bolts and reacting against the adjacent clamping member, means pivoted on said adjacent clamping member for normally holding said levers stationary, suspension means, and means operable upon movement of the suspension means beyond a predetermined extent for releasing said holding means. 125

6. A conductor suspension clamp comprising upper and lower clamping members engageable upon a conductor, levers located above the clamping members and reacting downwardly thereon, means pivoted on the upper clamping member normally holding said levers against movement whereby they will maintain the clamping members in clamped engagement upon the conductor, suspension means, and means cooperating with the suspension means for releasing said levers. 140

7. A conductor suspension clamp comprising upper and lower clamping members disposable upon a conductor, U-bolts carried by the lower clamping member and straddling the upper one, levers having toe portions engaged within the bights of the U-bolts and having heel portions reacting against the upper clamping member, re- 145

- taining means normally engaging the inner ends of the levers, suspension means, and means engageable by the suspension means upon movement thereof beyond a predetermined extent for 5 moving said retaining means out of engagement with the levers. 80
8. A conductor suspension clamp comprising upper and lower clamping members engageable upon a conductor, U-bolts carried by the lower 10 clamping member and straddling the upper one, levers reacting against the bight portions of the U-bolts and the upper clamping member for maintaining the clamping members in clamping engagement upon the conductor, pivoted means 15 on the upper clamping member normally engaging the inner ends of said levers for maintaining them effective, and suspension means engageable with said pivoted means upon movement beyond a predetermined extent for rendering the levers ineffective. 90
9. A conductor suspension clamp comprising upper and lower clamping members, bolts carried by the lower clamping member and extending over the upper one, levers reacting against 20 said bolts and the upper clamping member for normally maintaining a clamping relation, members pivoted on the upper clamping member and normally overlying the inner ends of said levers for maintaining them effective, and suspension 25 means for the clamp engageable with said pivoted members for moving them out of engagement with the levers and releasing the latter when the suspension means moves beyond a predetermined extent, said pivoted members having 30 outstanding portions embracing the suspension means in spaced relation thereto for enabling the suspension means to have limited movement before engaging said pivoted members. 100
- 35 10. A conductor suspension clamp comprising upper and lower clamping members, bolts carried by the lower clamping member and extending over the upper one, levers reacting against 40 said bolts and the upper clamping member for normally maintaining a clamping relation, members pivoted on the upper clamping member and normally overlying the inner ends of said levers for maintaining them effective, and suspension 45 means for the clamp engageable with said pivoted members for moving them out of engagement with the levers and releasing the latter when the suspension means moves beyond a predetermined extent, said pivoted members having 50 outstanding portions embracing the suspension means in spaced relation thereto for enabling the suspension means to have limited movement before engaging said pivoted members. 110
